UNITED STATES PATENT OFFICE.

GEORGE ALBERT CHADDOCK, OF BROAD GREEN, LIVERPOOL, ENGLAND.

MECHANICAL AIR-BORNE SHIP.

1,229,713.

Specification of Letters Patent. Patented June 12, 1917.

Application filed April 24, 1916. Serial No. 93,295.

To all whom it may concern:

Be it known that I, GEORGE ALBERT CHADDOCK, a subject of the King of Great Britain and Ireland, of 8 Staplands road, Broad Green, Liverpool, England, master mariner, inventor, and manufacturer, have invented certain new and useful Improvements in Mechanical Air-Borne Ships, of which the following is a specification.

10 This invention has for its object the production of a stable mechanical air ship, capable of alighting on or rising from water or land in a limited area and in any kind of weather. To better illustrate the nature of the improvements in this new form of mechanical air ship and the scope of their usefulness, it is necessary to refer to existing forms of air-craft. In the first place, the lighter-than-air form of ship has advantages for long distance travel and carrying capacity, but is not commercially practical on account of the supply of gas required and the necessity for special garages, in addition to which the vessel itself 20 is too unwieldy for practical purposes, and is also entirely unsuitable for alighting on or rising from water. In contrast, the mechanical ship described herein will possess advantages embodied in lighter-than-air ships without their disadvantages. Secondly aeroplanes and seaplanes which are only airborne when in motion through the atmosphere, cannot by their principles of construction become commercially useful, 30 because, for one reason, they are not capable of being controlled so as to land gradually, in a limited area, which maneuver cannot be effected by craft relying entirely on planes for their support when suspended in 40 the air. A contrast may be here made to vessels propelled through water. In this case length of hull is material for purposes of speed and dead weight carrying capacity. In this sense the aeroplane is a new de- 45 parture inasmuch as, breadth rather than length becomes the ruling factor governing the weight that can be carried, thereby imposing severe limitations and increased dangers and difficulties, whereas this invention is designed among other features to provide a really stable ship of a relatively greater length than breadth, thereby adding materially to her structural strength as well as stability, speed, and carrying capacity. 50 One of the material features of this invention arises from the resistance offered by

a fluid to the progress of a vessel therethrough which is of vital importance in any form of air ship because in very strong winds, the concentrated pressure of the air 60 upon the body of the vessel, and its accessories becomes a serious consideration from the point of view of making headway in the teeth of a strong wind viz; through a fluid which is itself in rapid motion. In this 65 respect vessels supported entirely on planes are at the greatest disadvantage and are impracticable for such purpose, as the numerous supports to the planes, the struts and stays necessary thereto, retard her progress and diminish her buoyancy.

A material part of my invention is to provide the equivalent of this plane lifting force as far as possible without the retarding influences such as operate with supporting struts and stays and other impediments of a fragile nature common to aeroplanes, as, where such are resorted to in my mechanical ship, they will, if fitted, be utilized for excess weight or carrying capacity when 80 owing to the structure of the ship the stays can be stayed to better advantage. With the foregoing illustrations indicating some of the ground work on which my invention is based I now proceed to describe the ship 85 and the mechanical means for combined lifting and propulsion thereof.

According to this invention the ship is preferably constructed on cylindrical lines. The center or other portions where lifting 90 devices are fitted, whether one or more, is open to the atmosphere above and below except for the keel and strengthening girders above and below, or any strengthening stays, or other strengtheners, or overhead netting 95 provided as a safeguard against bombs or the like. The lower part of the open center or other portions of the ship below the lifting devices is formed into a series of planes so contoured or shaped that the exterior air may act upon the under surface of such planes and by the reaction due to the impact arising from the welling up of the downcast air, billows are set up which assist in raising the ship or enable it to 100 achieve a skimming action whether in the air or on the water surface. The lifting devices, say in the form of propellers, may be driven by one or a series of engine units, and means are provided for adjusting the 110 direction of thrust of the propellers in such manner as to admit of their action operat-

ing vertically or with an inclination ahead or astern. The bow and stern ends of the ship are preferably bulkheaded off. A separate propeller may be fitted to the stern of the ship, and fin rudders provided for elevating, depressing, and laterally steering the vessel. Collapsible auxiliary supporting planes may also be fitted at the sides of the ship, such planes being adapted to be 10 opened out when in use or folded snug to the ship's side.

The invention is illustrated in the accompanying drawings in which Figure 1 is a longitudinal vertical section of an air-ship, 15 Fig. 2, being a plan of Fig. 1, showing the propellers arranged in twin formation. Fig. 3, is a cross section through the air-ship of Fig. 2, and Fig. 4, is a detail view to a larger scale showing a suitable means for controlling the angular deflection fore and aft of the lifting propellers. Fig. 5, is a cross section showing a modified form where a single series of propellers is provided instead of the twin arrangement of propellers shown 25 in Figs. 1 to 4. Fig. 6, is a diagrammatic view showing the means for articulating together and operating the elevating fin rudders.

The ship 1 as mentioned is preferably constructed on substantially cylindrical lines, 30 as indicated in Fig. 3, the lower part of the cylindrical section being open and the front and rear ends 2, 3, of the body being tapered off as shown. The central portion of 35 the ship is open above and below between the fore and aft bulk heads 4, 5, and is stayed across this opening by arched ribs 6, which form with the curved longitudinal side walls 7 a skeleton framework. The lifting devices consist of propellers 8 which in the 40 form shown are driven from a series of separate engine units 9 mounted on transverse platform frames 10. The propellers are mounted on the sleeves 11, which rotate on 45 rods 15 and are driven by bevel wheels 12, 13, from the engines 9 and the lower ends of the rods 15 are so mounted that they may swing radially about the axis of the driving bevel 13, during this movement. The propeller sleeves 11 have ball or antifriction 50 thrust elements 14 carried from the rods 15, which latter do not rotate axially. These upper rods 15 are provided with T-shaped heads 16, Fig. 4, to one side 17 of which is 55 connected a chain, wire rope, or the like flexible element 18 running from the winch 19 through the arched girders 20 to the pulley 21 at the rear of the ship, whence the flexible rope element returns to the winch 60 19, the return stretch passing loosely through the opposite sides of the T-heads at 18. The upward thrust of the propellers is taken by the shoulders 22 on the upper rods 15, which bear through a ball thrust or 65 otherwise against the girders 20, side play

of the propeller shafts being prevented by the engagement of the neck 23 in the groove formed between the girders 20. The flexible rope 18 or other element is guided over the grooved rollers 24, which are arranged 70 around the arch girders 20 the rope passing straight across from the termination of one arch girder to the next and so on in sequence throughout the ship. The propellers as shown are arranged in twin formation 75 down both sides of the ship, and each longitudinal series of propellers is wholly or partially connected and controlled by a separate flexible rope. With such an arrangement by operating the winch drum 19 the 80 angular position of the propeller shafts 11 may be set to incline ahead or astern. The coupling of the non-rotating shaft 15 and the revoluble propeller shaft 11 is made as an antifriction device. In this way the engine continuing to work at full speed the 85 propellers may be adjusted for either raising the ship vertically or driving it ahead or astern while in suspension. All the gearing, and wheels are incased in suitable lubricating boxes, and made watertight. The forepart 2, of the ship is inclosed by the outer tapered casing, the bulkhead 4, the 90 watertight platform 4^a, and the first rearwardly inclined plane 4^b. Similarly the rear 95 compartment of the ship is made watertight by the tapered casing 3, bulkhead 5 and watertight platform 5^a. Intermediate deck platforms 4^c, 5^c, are also fitted.

Below the propellers 8 are disposed the 10 planes 25 having rear surfaces 26 and lower planes 27. Below each pair of propellers therefore is a three plane unit, producing a corresponding series of outlets *a*, the downward pressure of the air stream set up by the propellers 8 issuing by these outlets *a* and the lower planes 27 acting, when the ship is in motion or hovering, as lifting planes, the air billows beneath the ship impinging upon these lower planes, and a skimming and raising action of the ship taking place. The means such as controlling levers and the like for operating the movable fins and steering gear, to be hereinafter referred to, are led to the navigating room or 113 other compartment of the ship. The arrangement for operating the elevating fins 28, 29, is shown diagrammatically in Figs. 2 and 6, where the forward fins 28 are raised or lowered above and below the level of the 115 web 30 by means of the shaft 31 operated by a handle 31^a and fitted with rods 32 connected by ropes 33 to the fore and aft shafts, and other ropes 34 connect the pulleys 32 to the fins 28, 29. Similarly the rudders 35 for 120 steering are operated from the wheel 36 by way of the ropes 37 passing around guide pulleys 38 to a tiller 39 connected to the rudder head 40. An additional propeller 41 may be fitted at the stern of the ship, driven 125 130

by a separate engine unit 42. For the purpose of controlling or assisting to regulate, the ascending and descending of the ship, planes 42', in the form of collapsible fins 5 may be fitted on each side, forward and aft, which fins would add to the lifting power of the ship under certain conditions or retard her descent, as well as be available for depressing or lifting the bow and stern as 10 desired. These planes 42 when not in use lie in the dotted position Fig. 3. snug against the ship's cylindrical side, but could be opened out by the control ropes 43 to the position shown. 15 For easy control these fins 42 are preferably operated by a connecting rod running across the vessel and engaging with the fins on each side in such manner that the fins may be operated simultaneously, so that if 20 desired the bow fins could be set for raising the prow and the stern fins for depressing the after end for rapid maneuvering. To the cross bar operating the fins would be attached a lever engaging with a fixed 25 notched quadrant, and so arranged as to prevent the fins being unduly depressed or raised. These controls as well as all other controls could be led to and operated from the conning tower. The machinery and fuel 30 being well down below the driving shafts, the ship would be extremely stable. Pendulum or other suitable indicators could be carried in the conning tower, to regulate or control an even keel. 35 As the length of the vessel will be preferably very much greater than her beam, it will be obvious from her depth and length and the fact that propellers could be fitted at each end that there will be a very considerable field for planes which may be fitted at each side from the water level forward to aft, on the broad part of the ship. These planes may rise in steps and stairs at the 40 sides and may be also carried across the vessel on the upper part thereof clear of the lifting devices. In considering the proposition of planes that may be fitted as auxiliaries to increase carrying capacity the speed of the vessel must also be considered in the 45 light of resistance of a fluid which is itself in motion and the fact that the propeller's efficiency is limited under the conditions under which it now works; therefore one of the features of this invention is to provide a ship capable of making an ocean passage against the varying winds which may be encountered. 50 A further feature of my mechanical airship is to provide means to minimize the difficulties of driving a ship through such a light fluid as air when it is moving rapidly in a direction opposed to the ship's progress. This is a material reason for dispensing with 55 all opposing surfaces tending to impede her progress. Even the fins previously de-

scribed should be dispensed with if it is found possible to do so, as it is preferable to have a ship without any obstructing surface or impediments.

Oil bunkers 44 are provided between the outer side skin 7 and the inner side members 45 which form the vertical walls of the trunkways, the lower parts 46 inclosed between the cylindrical sides 7, the inner walls 45, and the oil tanks 44, forming longitudinal pontoons throughout the ship's sides which make it water buoyant. The ship when waterborne floats approximately with reference to the water level *b* as shown in Fig. 3. Longitudinal passage ways 47 for the crew or passengers to pass from the fore to the aft compartment of the ship are provided, such tanks or passage ways being isolated by bulkhead doors 48. 70 75

By fitting the propellers in pairs as shown 80 rotating in opposite directions, the disadvantage attaching to a single arrangement of the propellers is avoided the air being prevented from chasing around with the propellers and a more solid axial thrust being 90 obtained, while by disposing the driving mechanism and the propellers, their shafts, and stays, within the stream line of the ship a greater efficiency is insured. 85

If desired as shown in the modification 95 Fig. 5., a single series of propellers 8^a may be substituted for the twin arrangement shown.

The portions inclosed by the planes 25, 26, 27, and the space below the decks 4^c, 5^c, may 100 be filled with some gas lighter than air, and a more buoyant type of ship obtained.

By making the body of the ship practically open in the center no ice or snow may 105 lodge on the top, and the downward air streams set up by the propellers being warmed by the engines, no water may freeze or lodge in the trunkways.

As the engines in such a ship will be very powerful, they are preferably placed as centrally as possible and as close as practical to the lifting devices. 110

The means herein described will enable heavy air- and waterborne ships to be driven 115 against opposing winds, and will afford such control as to make them commercially practical.

With an air and waterborne ship constructed as described its conditions would approximate to those of an ordinary sea 120 going vessel which is buoyantly supported from beneath in a fluid much denser than that above the vessel, the action of the propellers in the present invention setting up a reduced pressure above the ship and increasing 125 the pressure of the fluid below.

I claim.

1. A mechanical air and water-borne ship of substantially cylindrical section, tapered ends to said ship, inclosed compartments at 130

- the ends of the ship platformed and bulk-headed off from the remainder of the vessel, a central portion in the vessel open above and below, and longitudinal pontoons extending throughout the ship's sides.
2. A mechanical air and water-borne ship of substantially cylindrical section, tapered ends to said ship, inclosed compartments at the ends of the ship platformed and bulk-headed off from the remainder of the vessel, a central portion in the vessel open above and below, a series of propellers disposed in the central portion, means for varying the angular inclination of the propellers, and longitudinal pontoons extending throughout the ship's sides.
3. A mechanical air and water-borne ship of substantially cylindrical section, tapered ends to said ship, inclosed compartments at the ends of the ship platformed and bulk-headed off from the remainder of the vessel, a series of trunkways at the lower open part of such central portion, the thwartship inclosing sides of such trunkways being arranged as a series of planes, a series of propellers disposed in the central portion, means for varying the angular inclination of the propellers, and longitudinal pontoons extending throughout the ship's sides.
4. A mechanical air and water-borne ship of substantially cylindrical section, tapered ends to said ship, inclosed compartments at the ends of the ship platformed and bulk-headed off from the remainder of the vessel, a series of trunkways at the lower open part of such central portion, the thwartship inclosing sides of such trunkways being arranged as a series of planes, a series of propellers disposed in the central portion, means for varying the angular inclination of the propellers, longitudinal pontoons extending throughout the ship's sides, elevating and depressing planes horizontally disposed at the bow and stern of the ship, a vertically disposed rudder at the stern, and means for operating the planes and the rudder.
5. A mechanical air and waterborne ship of substantially cylindrical section tapered ends to said ship, inclosed compartments at the ends of the ship platformed and bulk-headed off from the remainder of the vessel, a central portion in the vessel open above and below, a series of propellers disposed in the central portion, said propellers being arranged in twin formation and the propellers in each pair rotating in opposite directions, means for varying the angular inclination of the propellers, and longitudinal pontoons extending throughout the ship's sides.
6. In an air ship, a body having its upper and lower portions open throughout its length, means positioned centrally of the body and throughout its length for propelling the air ship, and means for adjusting the propelling means for controlling the movements of the ship.
7. In an air ship, an elongated body having its upper and lower portions open, horizontally operating propellers supported in pairs throughout the length of the body, a vertically adjustable shaft supporting each propeller, means adjacent the upper end of each shaft for adjusting the shafts simultaneously at various angular inclinations for controlling the movements of the ship, and longitudinal pontoons extending throughout the ship's sides.
8. In an air ship, an elongated body having its upper and lower portions open, propellers supported within the body and having supporting rods, arch girders having shoulders supported above the supporting rods, said rods having T-shaped heads engaging the shoulders of the girders, and means for moving the supporting rods within the arch shaped girders for moving the propellers to various angles.
- In testimony whereof I affix my signature in presence of two witnesses.
